UNITED STATES PATENT OFFICE.

JOHN H. GWINNER, OF HUGHESVILLE, PENNSYLVANIA.

SHOE-BLACKING APPARATUS.

SPECIFICATION forming part of Letters Patent No. 245,819, dated August 16, 1881.

Application filed June 18, 1881. (Model.)

To all whom it may concern:

Be it known that I, JOHN HENRY GWINNER, of Hughesville, in the county of Lycoming and State of Pennsylvania, have invented certain 5 useful Improvements in Shoe-Blacking Apparatus, of which the following is a specification.

The object of my invention is to provide a new and improved blacking apparatus.

10 The invention relates to a box provided with compartments for slippers, blacking-brushes, shoe-dressing bottles, &c., which compartments are provided with swinging lids, to one of which a reversible foot-rest, that can be adjusted for right or left handed persons, is attached. The lid of the box has a blacking-box-holding frame pivoted to its under side, in which frame the blacking-box is held by suitable thumb-screws, and the lid is also provided with a rubber bulb containing water, which is conducted by a suitable tube to a nozzle projecting from the under side of the lid, so that when the bulb is compressed a small quantity of water will be squirted upon the blacking-box or on the brush.

15 In the accompanying drawings, Figure 1 is a perspective view of my improved blacking apparatus, the lid of the box being raised and the lids of the compartments closed. Fig. 2 is 20 a perspective of the same, showing the lid of the box raised, the blacking-box-holding frame lowered, and the compartment-lid with the foot-rest opened. Fig. 3 is a cross-sectional elevation of the same, showing the lid of the box raised and one of the compartment-lids 25 raised to support the lid of the box. Fig. 4 is a plan view of the same, showing the lids of the compartments removed.

Similar letters of reference indicate corresponding parts.

30 The box A is divided by the partitions B' and B² into the front compartments, A', for slippers or shoes, the rear compartment, A², for blacking-brushes, and the rear compartment, A³, for shoe-dressing bottles, boot-grease bottles, &c.

35 A rod, C, extends across the box from side to side, above the partition B', and forms a support for the lids C' and C² of the compartments A', A², and A³, respectively, these lids being hinged to each other on the upper sur-

faces. The adjoining edges of these lids are provided with longitudinal grooves u, containing the rod C when the lids are closed. The lids C' and C² are provided with loops or handles b b for raising them.

40 A foot-rest, D, formed of a pivoted central part, D', and a fixed heel part, D², and a toe part, D³, is attached to the under side of the lid C², the pivoted central part, D', being provided with an eyelet, c, at each side.

45 A frame, E, is pivoted to the under side of the lid F of the box A, near the bottom of this lid, this frame being provided with a central opening for receiving the blacking-box G, which is held therein by the thumb-screws H. The frame E is provided with a hook, J, on its inner surface at the outer edge. A rubber bulb, K, is contained in the lid F, and from this bulb a tube, L, leads to a nozzle, M, projecting from the under side of the lid F.

50 The lid F is provided on the under side with a hook or eye, R, below the bulb K.

55 The box A is preferably provided with casters N.

60 The lid F is provided with hooks O, which catch on pins P P of the box A or with another suitable lock.

65 The box A may be made plain or it may be upholstered.

70 The operation is as follows: If the lid F is to be held open so that the slippers can be removed from the compartment A' the lid C' is raised and held as shown in Fig. 3. If the shoes are to be blackened the lid C² is folded down over the lid C', so that the foot-rest will be in the proper position, as shown in Fig. 2, and the hook J of the frame E is hooked into one of the eyelets c of the central pivoted part, D', of the foot-rest to hold the same in position.

75 As shown, the foot-rest is in position for a person using his righthand in blacking boots; but if it is to be used by a left-handed person the central pivoted part, D', is reversed and is secured by means of the opposite eyelet and the hook J. If the blacking-paste contained in the box G is to be moistened or dissolved the bulb K is compressed, upon which a stream of water issues from the nozzle M upon the blacking or brush. The bulb K is filled with 80 water by attaching a thin rubber tube leading to a vessel containing water to the nozzle

M. The bulb K is compressed, and when released the suction draws a quantity of water into the bulb K. When not in use the frame E is held up against the lid F by passing the hook J of the frame E into the hook or eye R of the lid F.

Having thus fully described my invention, I claim as new and desire to secure by Letters Patent—

- 10 1. In a shoe-blacking apparatus, the combination, with the box A, of the lid F of the blacking-box-holding frame E, the foot-rest D on the lower lid, C², of the bulb K, tube L, and nozzle M in the lid F, substantially as herein shown and described, and for the purpose set forth.
- 15 2. In a shoe-blacking apparatus, the foot-rest D, constructed, substantially as herein

shown and described, with fixed end parts, D² and D³, with a pivoted central part, D', as and for the purpose set forth.

3. In a shoe-blacking apparatus, the combination, with the lid F, of the blacking-box-holding frame E, the hook J, the central pivoted part, D', of the foot-rest D, and the eyelets e, substantially as herein shown and described, and for the purpose set forth.

4. The combination, with the lids C' C², pivoted to each other on the upper side and provided with grooves u in the adjoining edges, of the rod C, substantially as shown and described, and for the purpose set forth.

JOHN HENRY GWINNER.
